[57] CLAIM

The ornamental design for a medical sampler device, essentially as shown and described.

DESCRIPTION

FIG. 1 is a front perspective view of a medical sampler device showing my new design;

FIG. 2 is a top plan view thereof;

FIG. 3 is a left side view thereof;

FIG. 4 is a front plan view thereof;

FIG. 5 is a right side view thereof;

FIG. 6 is a rear view thereof;

FIG. 7 is a top plan view thereof;

FIG. 8 is an enlarged cutaway view showing the internal sampling cells;

FIG. 9 is a top plan view of a second embodiment of a medical sampler showing my new design;

FIG. 10 is a left side view thereof;

FIG. 11 is a front plan view thereof;

FIG. 12 is a right side view thereof;

FIG. 13 is a rear view thereof;

FIG. 14 is a top plan view thereof; and

FIG. 15 is an enlarged cutaway view showing the second embodiment of the internal sampling cells.
